UNITED STATES PATENT OFFICE.

JAMES F. TOOHEY, OF DETROIT, MICHIGAN.

TICKET HOLDER.

1,416,909.

Specification of Letters Patent. Patented May 23, 1922.

Application filed March 12, 1921. Serial No. 451,723.

To all whom it may concern:

Be it known that I, JAMES F. TOOHEY, a citizen of the United States, residing at Detroit, in the county of Wayne and State of Michigan, have invented certain new and useful Improvements in Ticket Holders, of which the following is a specification.

This invention relates to ticket holders, the primary object of which is to provide a receptacle or holder which is especially adapted for carrying a plurality of tickets, such for instance, as street car tickets, etc., the device being of such a character as to position one of the tickets at all times so that it may be conveniently grasped by the user.

Another object of the invention is to provide a simplified structure which may be carried in the vest pocket, purse, or the like, and which will permit a ticket, or series of tickets to be easily and expeditiously removed therefrom.

The above and other objects of this invention will be in part described and in part understood from the following description of the present preferred embodiment of the invention taken in connection with the accompanying drawings, wherein:

Fig. 1, is a top plan view of the device constructed in accordance with this invention, the closure thereof being shown in open position.

Fig. 2, is a longitudinal sectional view taken on the line 2—2 of Fig. 1, looking in the direction of the arrow.

Fig. 3, is a transverse sectional view taken on the line 3—3 of Fig. 1, looking in the direction of the arrow, and

Fig. 4, is a perspective view of the device showing the closure in a secured position.

The device of this invention consists of a body 5, made of wood or any other suitable material, and preferably of an oblong configuration. The body has a longitudinally extending recess 6 formed therein which extends through the longitudinal center of the body and opens through one end of the latter. Both ends of the body are preferably rounded, as indicated at 7, to permit convenient insertion and removal of the same in and from the pocket or pocket-book of the user, and to prevent undue bulging of the pocket or the like wherein the device may be inserted.

A plurality of spring fingers 8 are mounted in said body 5, each of said fingers con-

sisting of a metal strap, one end of which is engaged in the wall of the recess 6. The opposite end of each finger projects through a semi-circular recess 9, also formed in the wall of said recess, the free terminal of each finger projecting into the recess in close proximity to the top of the body 5. As shown to advantage in Fig. 3 the tickets are arranged in said recess 6 beneath the fingers 8 and are held from displacement by the latter. As a rule, the tickets are secured along their longitudinal edges and it is preferred to permit the free edge of the uppermost ticket to project upwardly so as to be conveniently grasped. As soon as this ticket has been removed the next ticket will be caused to automatically assume the same position since in removing the uppermost ticket pressure can be exerted thereon so as to flex the fingers 8 on one side upwardly so as to release the lateral margin of the next adjacent ticket. It is of course understood that the fingers 8 are very small and consequently are highly flexible and highly resilient.

Preferably, a casing 10 of leather, or any other suitable material, is mounted upon the body 5 and has one end thereof extended to form a closure 11. The closure 11 is equipped with a socket 12 which complements a stud 13, the latter being mounted upon the upper face of the casing 10 at the end of the recess 6. It is of course understood that the casing 10 has a portion thereof removed to expose the semi-circular recesses 9 and recess 6.

In use of this device, it will no doubt be apparent from the above that the tickets are folded and placed in the recess 6 beneath the fingers 8, pursuant to which the closure 11 is secured by engaging the socket 12 with the stud 13. When it is desired to remove one or more of the tickets, the closure is opened in an obvious manner and the tickets pulled upwardly in a manner as above described. By providing the recesses 9, it will be apparent that ample space for the expansion and contraction of said fingers, caused by the insertion and removal respectively of the tickets from said recess, is provided.

Various changes may be made in this device especially in the details of construction, proportion and arrangement of parts without departing from the spirit and scope of

the invention as covered by the appended claims.

What is claimed is:

1. A ticket holder including a body provided with a recess to receive tickets, and a casing mounted on said body and having one end thereof extended to provide a closure engageable over said recess to prevent accidental displacement of the tickets from said recess.
- 10 2. A ticket holder including a body provided with a recess to receive tickets, a plurality of resilient fingers mounted in the side walls of said recess and impinging said tickets to hold the latter in a compressed position, said fingers being flexible under pressure exerted upon the uppermost ticket to

permit removal of one or more of said tickets.

- 15 3. A ticket holder including a body provided with a ticket receiving recess and equipped with a plurality of resilient fingers to hold said tickets compressed in said recess, and a casing arranged on said body and having one end thereof extended to provide a closure for engagement over said ticket recess.

In testimony whereof I affix my signature in presence of two witnesses.

JAMES F. TOOHEY.
